(57) **CLAIM**

We claim the ornamental design for a module-mounting base for an industrial control system, as shown and described.

DESCRIPTION

FIG. 1 is a front and right side perspective view of a module-mounting base for an industrial control system showing our new design;

FIG. 2 is a rear and right side perspective view thereof;

FIG. 3 is a front elevation view thereof;

FIG. 4 is a top plan view thereof;

FIG. 5 is a right side elevation view thereof;

FIG. 6 is a left side elevation view thereof;

FIG. 7 is a rear elevation view thereof; and,

FIG. 8 is a bottom plan view thereof.

The broken line portion of the figure drawings is included to show unclaimed subject matter only and forms no part of the claimed design.
